UNITED STATES PATENT OFFICE.

RUDOLF E. HELLMUND, OF SWISSVALE, PENNSYLVANIA, ASSIGNOR TO WESTINGHOUSE ELECTRIC AND MANUFACTURING COMPANY, A CORPORATION OF PENNSYLVANIA.

DYNAMO-ELECTRIC MACHINE.

1,373,002.

Specification of Letters Patent.

Patented Mar. 29, 1921.

Application filed May 16, 1916. Serial No. 97,837.

To all whom it may concern:

Be it known that I, RUDOLF E. HELLMUND, a subject of the German Emperor, and a resident of Swissvale, in the county 5 of Allegheny and State of Pennsylvania, have invented a new and useful Improvement in Dynamo-Electric Machines, of which the following is a specification.

My invention relates to dynamo-electric 10 machines, and it has particular relation to systems of ventilation for such machines.

One object of my invention is to provide 15 an improved system of forced ventilation for motors of the semi-inclosed type that will insure uniform distribution of the cooling medium throughout the motor.

A further object of my invention is to 20 provide a system of ventilation that may be advantageously applied to motors which are arranged to operate in pairs.

It has heretofore been proposed to provide 25 the relatively rotatable core members of dynamo-electric machines with longitudinal ducts for the passage of a cooling air. However, when an external source was employed to create a circulation of the air, it was found that a greater volume of air 30 passed through the ducts in the stationary member than through the ducts in the rotating member. This resulted in undue heating of the latter member. By my invention, I provide means for guiding and forcing the air through the ducts in the rotatable member.

In the accompanying drawing, the figure 35 is a transverse sectional view of a motor embodying my invention, and comprises substantially semi-annular plates 1 and 2 between which is clamped a curved frame 3.

An annular magnetizable core member 4 is 40 composed of laminations and is secured between annular end-plates 5 that are of somewhat greater outside diameter than the laminations. The core member 4 is positioned on the frame 3 by spaced projections

45 provided on the inner surface thereof which fit between the end-plates. The member 4 and the plates 5 are provided with longitudinal passages 7, and additional longitudinal passages 8 are provided by the 50 spaces between the projections 6 and the outer surface of the core member 4. The frame 3 is provided with an opening 9 that is located adjacent to the left-hand end

plate 5. A second annular magnetizable core 55 member 10 is composed of laminations and is secured between end-plates 11 that are mounted on a spider 12. The spider 12 is keyed to a shaft 13 that is rotatably mounted in bearings 14 which are supported by 60 the plates 1 and 2, respectively. The core member 10 and the end-plates 11 are provided with longitudinal passages 15. Additional longitudinal passages 15 are provided between the web 12^a of the spider 12 65 and the inner surface of the core member 10. A winding 16 is located in suitable slots in the core member 10, and the end portions of the coils comprising the winding 16 are braced by an annular support 17. 70 The coil-support 17 has an inner curved surface, and circular plates 18, having curved surfaces similar to the inner surface of the support 17, are secured to the end plate 11 at points intermediate the passages 75 15. Substantially concentric passages 19 that bend toward the shaft 13 are thus provided between the plates 18 and the member 17. The plates 18 are respectively provided along their inner edges with vanes 20 that 80 project into the passages 19.

A casing 22, preferably formed of sheet metal, incloses the upper portions of the motor. The top plate 23 of the casing 22 is supported by the end-plates 5 of the core 85 member 4, thus providing closed passages 24 between the outer surfaces of the core members 4 and the casing 22. The side plates 25 of the casing 22 are supported by the bearings 14 and are spaced from the 90 ends of the winding 16 to provide chambers 26 and 27. An opening 28 is provided at the top of the chamber 26 at a point directly above the axis of the motor. The opening 28 is connected to suitable external 95 means for creating a circulation of air, such as fans 30, by means of tubes 31.

Having fully described the various parts of my device, the action of the ventilating system during the operation of the motors 100 is as follows: When the fans 30 are operated, air is forced into the chamber 26 and a portion thereof passes through the longitudinal passages 7 and 8 of the core member 4. The remainder of the air is delivered to the 105 passages 19 where the rotation of the vanes 20 carried by the core member 10, acting in conjunction with the plates 18, sets the air

into rotation and forces it into the curved passages 19 at a slightly increased pressure and through the longitudinal passages 15. The air is discharged from the longitudinal 5 passages 15 into a collecting chamber and passes outside of the frame 3 through the opening 9.

It is apparent from the foregoing that the ventilating air is equally distributed 10 within the motors and that continuous passage of the air through the rotating member is insured by the presence of the guiding passages and vanes.

While I have shown my invention in a 15 simple and preferred form, it is not so limited but is capable of various minor changes and modifications within the scope of the appended claims.

I claim as my invention:

20 1. In a dynamo-electric machine, the combination with relatively rotatable magnetizable members provided with longitudinal passages, and an inclosing casing for said

members, of external means for creating a circulation of air through said machine, and 25 further means located within said casing for setting the air into rotation and for slightly raising the pressure thereof before entering the passages in the rotatable member.

2. In a dynamo-electric machine, the combination with relatively rotatable magnetizable members provided with longitudinal passages, and an inclosing casing for said member, of external means for creating a circulation of air through said machine and 30 35 vanes carried by the rotatable member and coacting barrier members for setting the air within said casing into rotation and for slightly raising the pressure thereof before entering the passages in said rotatable 40 member.

In testimony whereof I have hereunto subscribed my name this 29th day of April, 1916.

RUDOLF E. HELLMUND.
